AIR OR OTHER CURRENT SEPARATOR

George Holt Fraser, Brooklyn, N. Y.

Original application January 10, 1935, Serial No. 1,173. Divided and this application May 18, 1936, Serial No. 80,258. Renewed May 13, 1939

20 Claims. (Cl. 209—139)

This application is a division of my application Serial No. 1,173 filed Jan. 10, 1935, and is in part a continuation of my application Serial No. 606,407, now Patent 2,113,586, filed April 20, 1932.

5 This invention relates to separators for separating fine from coarse material by a fluid current.

Some such separators have a settling chamber, a separating chamber having a lower current inlet and an upward current passage and an upper current outlet in communication therewith and affording an endless current passage or path extended up through and down around said separating chamber and in communication with said 10 chambers, a rotary distributor for the supply and distribution of material to be separated within the upward passage, and vertically or radially movably adjustable, for varying the height or width of the zone of distribution, for varying the separation of said material, variable current circulation means or rotary blower means for upflowing a fluid current through said upward passage for separating fine material therein and floating it therefrom into said settling chamber, and variable for varying the velocity of circulation of said 15 current, for varying said separation, rotary current space variation means adjacent the upper outlet for defining the space through which said current may flow, and vertically or radially movably adjustable for varying said space, for varying the velocity of the current, for varying the separation, and a return current passage in communication from the settling chamber to the lower inlet.

35 In some such separators the speed of rotation of the distributor has been variable, for varying the rate of supply of material, or for varying the velocity of its distribution, and the speed of rotation of the blower has been variable for varying the velocity of the circulation of the current, for varying the separation, and these variations have been automatically simultaneously effected in response to variations in the weight of unseparated material discharged from the separating chamber on 40 to a weight responsive tailings cone, and in some such separators the current circulation means comprised fan blades which were manually adjustable to vary their superficial area, for thereby varying the velocity of said circulation.

45 Some types of such separators have relatively revoluble shafts, driven by relatively variable drivers, for relatively rotating the distributor and the blower at variable speeds, and other types rotate these at like speed by a single shaft common to both, and some types of such separators have

a central feed pipe within a tubular drive shaft, and other types have an annular feed conduit around an inner drive shaft, which pipe or conduit has terminated in a supply orifice above and adjacent the distribution means. 5

My present invention may be used with either of said types, and relates especially to such separators in which the current space variation means and the distribution means are vertically spaced a substantial distance from each other, for affording a substantial selection chamber therebetween, and in which the upper outlet is above this selection chamber and is spaced a substantial distance above the distribution means and is around and adjacent the current space variation means, 10 and in which both the latter are movably adjustable relatively to the upper outlet, for varying adjacent the latter the space through which the current from the separating chamber may flow and for varying the zone of distribution from a 15 substantial distance below the space variation means, for varying the separation.

One air separator is shown in my Patent No. 1,542,050 dated June 16, 1925, in which I have shown and claimed a distributor which during its 20 rotation can be vertically lowered relatively to its drive shaft, and upthoer means rotatable with it for upthoing material around it, and vertical interceptor vanes across the return current passage, for intercepting material floating therein, and 25 non-rotary closure means for the ends of said vanes, and variable current circulation means comprising rotary fan blades, the superficial area of which could be manually varied by a special 30 operation during their rotation, for varying the velocity of circulation of the current, and in which the non-rotary walls of the separating chamber itself were manually vertically adjustable to maintain their relation to the vertically adjustable distributor, for preventing variation of the 35 volumetric area, or of the direction of the upward current passage, around and above the distributor with vertical adjustment of the latter.

Another air separator is shown in my Patent No. 1,834,095 dated Dec. 1, 1931, in which I have 40 shown and claimed such current regulation means as a rotary and radially adjustable vertical upper valve and a rotary and vertically adjustable upper baffle at the upper outlet, and each carried from the fan spokes by a lever fulcrumed thereon and 45 rotatable therewith, which when its rotation was stopped was operable to radially adjust the valve and vertically adjust the baffle at the same time, which required stoppage of operation.

Another air separator is shown in my Patent 55

No. 1,876,516 dated Sept. 6, 1932, in which I have shown non-rotary radially adjustable segments spaced around a distributor disc for varying the distribution and current space therearound, and have claimed any adjustment means comprising radially adjustable plates for varying the width of distribution and current spaces around the zone of distribution, and have shown and claimed a non-rotary valve within the tailings cone, and a vent outlet within the tailings cone, and variable speed drivers for the distributor and blower which are varied by vertical movement of a weight responsive tailings cone, for automatically varying the speed of rotation of the distributor, for varying the rate of the supply of material to be separated and the velocity of its distribution, and for automatically simultaneously varying the speed of rotation of the blower, for varying the velocity of the circulation of the current coincidently with said variation of said supply and of said velocity of said distribution.

Another air separator is shown in my Patent No. 1,987,615 dated Jan. 15, 1935, in which I have shown a distributor consisting of a rotary conical ring of inwardly and outwardly movable segments, which is rotatable and adjustable relatively to a conical upper baffle below the upper outlet, and have claimed such a baffle, and a vent outlet within the separating chamber, and variable drivers for the distributor and blower which are varied by a weight responsive tailings cone, for automatically varying the speed of rotation of the distributor, for varying the rate of supply of material to be separated and the velocity of distribution thereof, and for simultaneously varying the speed of rotation of the blower, for varying the velocity of the circulation of the current coincidently with said variation in the rate of said supply and in the velocity of said distribution.

Another air separator is shown in my Patent No. 1,992,942 dated March 5, 1935, in which I have shown a distributor and its hub or lower baffle adjacent and in vertically fixed relation to it which are fixed on a lower end of and move vertically with their drive shaft which is revolvably mounted on and movable with an upwardly and downwardly movable bearing, carried by a sustainer lever which is sustained and moved by a weight responsive tailings cone, and have claimed any rotary distributor or baffle so mounted, sustained and moved.

Another air separator is shown in my application Serial No. 714,961, now Patent 2,055,485, filed March 10, 1934, as a continuation in part of my application Serial No. 687,359 which in part matured into Patent No. 1,987,615 granted January 15, 1935, and of my application Serial No. 514,199 filed Feb. 7, 1931, and of my application Serial No. 584,140 filed Dec. 31, 1931, in which application Serial No. 714,961 I have shown a distributor and lower baffle each comprising a rotary ring of inwardly and outwardly slidable segments for radially varying their size, and have claimed a rotary distributor or baffle comprising a ring of segments slidably adjustable by inward and outward movement.

Another air separator is shown in my application Serial No. 514,199, now Patent 2,055,484, filed Feb. 7, 1931, in which I have shown a distributor having a rotary ring of individually inwardly and outwardly slidably adjustable segments, and have claimed a rotary and vertically adjustable annular baffle spaced around and above the distributor, and an outwardly extended rotary valve mounted above the fan spokes and adjustable thereabove,

and vertically adjustable non-rotary valves, one conical, around the outer edges of the fan blades, and non-rotary flapper valves below the filter vanes.

Another air separator is shown in my application Serial No. 584,140 filed Dec. 31, 1931, in which I have shown and claimed a distributor and its lower baffle each having a rotary ring of segments which are collectively slidable relatively to upthrust means around the distributor, a conical annular baffle spaced around and above said segments, an upper valve and an upper baffle each surrounded by a ring of collectively radially slidable segments, means for coincidentally radially adjusting said segments, rotary beaters around a rotary ring of radially slidable segments which are collectively slidable relatively thereof, a rotary ring of inwardly and outwardly slidable segments above the separating chamber and slidable relatively to the outlet, a vertically adjustable rotary valve above the outlet, shown as adjustably depended by a screw from the fan spokes, jarrer hammers between the inner and outer casings, and collective adjustment means for collectively sliding the segments comprising oscillatory gearing, and current space variation means adjacent the outlet and movably adjustable by adjustment means mounted below the blower means or on a vertical axis, and successive current space variation means adjacent the outlet and coincidentally adjusted by coincident radial adjustment means common to both.

Another separator is shown in my application Serial No. 606,407 filed April 20, 1932, now Patent 2,113,586, of which this is in part a continuation, in which I have shown and claimed a distributor rotatably carried by an upwardly and downwardly movable bearing, and counterbalanced by a weighted lever, movable by one manipulation for vertically adjusting the distributor, a flat baffle and a flat valve connected by motion reversal means and rotatably mounted on another upwardly and downwardly movable bearing slidable on the distributor drive shaft, and counterbalanced by another weighted lever, movable by another manipulation for thereby reversely relatively adjusting the baffle and valve at the same time, and a flat rotary shelf as a closure under the interceptor vanes, and a rotary grooved ring as a closure around the tailings cone, and a conical rotary tailings retarder below the lower inlet and around the return current passage, and current space variation means adjacent the outlet and movably adjusted by adjustment means below said variation means and mounted below the blower and above the distributor.

Another separator is shown in my application Serial No. 628,678 filed August 13, 1932, in which I have shown and claimed fan spokes mounted a spaced distance below and extended up through a vertically adjustable distributor, and a flat upper baffle having spokes mounted a spaced distance below the fan spokes and extended up through the distributor, and a rotary inverted conical annular valve shown as around the fan spokes and having valve spokes mounted a spaced distance below and extended up through the distributor, the distributor adjuster being around and adjustable relatively to its shaft, and rotatably suspended on an upwardly and downwardly movable bearing within and encircled by the feed conduit, and the baffle and valve being suspended from within the drive shaft and rotatably mounted on bearings thereabove respectively, each bearing being upwardly and downwardly movable by a

separate lever and a separate manipulation, and I have claimed a vertically adjustable annular jet orifice round the filter vanes, and a rotary conical leakage resistor below the vanes, and a rotary 5 tubular deflector within the return current passage, the rotary parts being rotatable together and separately sustained and relatively slidably connected.

Another separator is shown in my application 10 Serial No. 628,679 filed August 13, 1932, in which I have shown and claimed a distributor rotatably mounted on a bearing slidable around its shaft and within the fan hub, a flat baffle rotatably mounted on a bearing around said bearing, and 15 a flat valve rotatably mounted on a bearing round the baffle bearing, these bearings being below the gear casing and slidable on a guide dependent therefrom, and each being upwardly and downwardly movable by a separate lever and a 20 separate manipulation, with a motion reversal lever between the flat baffle and a conical annular baffle below it, and I have claimed a vertically adjustable deflector around the interceptor vanes and a rotary conical trough below and for sealing 25 their lower ends, and a rotary retarder shelf within and above the lower inlet.

My said claimed constructions require separate manipulations for varying the zone of distribution and for varying the velocity of the circulation 30 of the current or the space through which the current may flow, and did not accomplish both simultaneously, coincidently, nor collectively, provision for which constituted a part of my original invention as originally set forth in 35 my said application Serial No. 606,407.

In my application Serial No. 55,423 filed Dec. 20, 1935, as a division, or a continuation in part, of my said application Serial No. 606,407, I have shown and claimed a distributor and a flat upper baffle and a flat upper valve which are vertically 40 adjustable at the same time by one manipulation, with a reverse motion connection between the distributor and the upper valve vertically moving the latter in reverse direction, to the vertical movement of the distributor by said manipulation, and have claimed coincident collective adjustment of a distributor and upper baffle or upper valve at the same time by one manipulation.

In my application Serial No. 93,210 filed July 29, 1936, as a division, or continuation in part, of my said application Serial No. 606,407, I have shown a lower distributor and a flat upper baffle which are vertically movable in the same direction at the same time, and a flat upper valve 50 which is simultaneously reversely vertically movable, and have claimed distributor suspension adjustment means above the distributor and by which it is suspended, movably mounted within and below the outer casing, and by which the upper baffle and upper valve are sustained from below the latter, revolvably with the blower, and revolvably connected to and operated by a non-rotary adjuster common to and sustaining the distributor, the baffle, a valve and the adjustment means, and by which at one manipulation the distributor and the upper baffle are adjusted in the same direction, and the valve is adjusted in a reverse direction, all simultaneously and 60 without stopping the operation, in which construction the adjustment means is shown as fulcrumed to a suspender depended from the blower.

In the said constructions shown in my said applications Serial Nos. 55,423 and 93,210, the space through which the current may flow was 65

diminished for decreasing the velocity of the current coincidentally with vertical elevation of the zone of distribution, and was increased for increasing the velocity of the current, coincidentally with depression of said zone.

In my application Serial No. 1,173 filed Jan. 10, 1935, of which this is a division or a continuation in part, I have shown a vertically adjustable lower distributor and a reversely vertically adjustable upper baffle, which are connected by a motion reversal connection which translates vertical movement of the lower distributor in one direction into vertical movement of the upper baffle in the reverse direction and simultaneously moves both, the distributor and its lower hub or baffle each having a rotary ring of radially slidably adjustable segments slidable coincidently with said vertical adjustment, and being surrounded by an annular baffle which is adjustable 15 relatively to the distributor and the upper baffle coincidently with adjustment thereof, and the upper baffle having an inner recessed portion of inverted conical shape around an inverted conical upper valve vertically fixed in relation to and carried by and movable with the distributor, all 20 being revolvably carried by a vertically movable bearing mounted on a counterbalanced lever, and all being simultaneously adjustable by one manipulation during their rotation, and all being encircled by the fan spokes; and have also 25 shown and claimed variable speed drivers for rotating the distributor and the fan blades at variable relative speeds, and a connection between said drivers and said bearing operable to 30 vary said speeds simultaneously with said adjustment of said distributor, and have claimed 35 said relatively adjustable lower distributor and upper baffle connected by a motion translation connection and simultaneously adjustable the one from and relatively to the other by one manipulation coincidently with the other, and said annular baffle relatively adjustable thereby simultaneously with adjustment thereof and by 40 said manipulation, and said recessed upper baffle around and movable reversely to a conical upper valve; and said radially slidable segments and vertically adjustable upper baffle connected by a motion translation connection and simultaneously relatively moved thereby coincidently 45 with adjustment of said lower distributor, and being revolvably connected below the distributor to the fan drive shaft and adjusted therefrom from below the distributor, and said operative connection between said parts and said variable driver means operable to vary the speed of rotation 50 transmitted from the latter simultaneously with variations in said adjustment thereof; and said rotary and relatively adjustable parts within and encircled by said fan spokes and adjustable relatively thereto.

In my application Serial No. 33,777 filed August 31, 1935, I have shown a separator having a relatively vertically adjustable lower distributor, lower baffle, annular baffle, upper baffle and upper valve, the annular baffle being 55 radially adjustable from within to around the upward current passage, and the lower baffle being simultaneously reversely radially adjustable, and all being revolvably suspended from a vertically adjustable bearing mounted on a counterbalanced lever and in operative relation to a variable speed driver common to, and the speed of rotation of which is automatically varied simultaneously with adjustment of, said parts, and have claimed coincident variable relative adjust- 60

ment of said parts, and radial adjustment of said annular baffle, and simultaneous reverse radial adjustment of the latter and said lower baffle, and adjustment means for said distributor, 5 baffles and valve, mounted below the blower and above the upper outlet, or extended radially outwardly of the latter, or on the blower or the fan blades.

My original invention as originally set forth in 10 my said application Serial No. 1,173 comprised as one feature an upper baffle carried from a lower distributor by a motion reversal connection operable to translate vertical movement of the lower distributor in one direction into vertical movement of the upper baffle in the reverse direction, and in the reverse direction to an annular baffle therebetween and to a vertically movable valve thereabove, all being simultaneously moved by one manipulation, to which the claims 15 in said application are directed; and comprised as another feature a construction without an upper baffle and comprising a vertically adjustable lower distributor and upper valve in vertically fixed relation and simultaneously vertically adjustable in the same direction and to the same extent at the same time, below the fan spokes and each carried by a vertically movable suspender revolvably carried by a vertically adjustable bearing mounted on a counterbalanced lever, 20 and both simultaneously adjusted by one manipulation thereof, which feature included an annular baffle movable from adjacent a distributor to adjacent an upper outlet coincidently with and in the same direction as and to a greater 25 extent than, and by vertical adjustment of, the distributor and upper valve, said distributor and its lower baffle each having a rotary ring of radially adjustable slidable segments, adjusted from above the lower baffle and coincidently with 30 vertical adjustment thereof, and from the distributor drive shaft thereabove, and variable speed drivers for rotating the distributor and the fan blades at variable relative speeds, and a connection between said drivers and said lever, 35 operable to vary said speeds simultaneously with adjustment of said valve or said annular baffle.

My present application pertains to said second features originally comprised in my said original application Serial No. 1,173 and aims to protect 40 said portion of my said original invention.

To this end in carrying out the preferred embodiment of my present invention as applied to a separator in which the separating chamber is in direct communication with the upper outlet, 45 and in which the current circulation means is rotatable at variable speed, and in which the current space variation means comprises an upper valve adjacent and movably adjustable relatively to the upper outlet, and in which the distribution means comprises a movably adjustable lower distributor, and in which adjustment means for said valve and distributor coincidently movably adjusts them, I preferably mount said valve and distributor in vertically fixed relation, and make 50 them vertically movable in the same direction and to the same extent at the same time, and revolvably suspended from a vertically adjustable upper bearing adjusted by one manipulation and thereby operable to simultaneously identically adjust the lower distributor and the upper valve, and I preferably provide an annular baffle intermediate the distributor and upper valve which is movable simultaneously therewith from adjacent the distributor, for affording a substantial precipitation chamber between the an-

nular baffle and the upper outlet, to adjacent the upper outlet, for eliminating such a chamber, and I preferably provide both said distributor and its hub or lower baffle with a rotary ring of radially adjustable slidable segments, and radially slidably adjust said segments from above and simultaneously with vertical adjustment of the distributor, and I preferably vary the speed of the latter and of the blower coincidently with adjustment of said valve or of said annular baffle. 10

For accomplishing this my invention provides various features of my improvement which I prefer to combine and apply and use together in any current separator as shown in the accompanying drawings in which—

Fig. 1 is a side elevation, partly cut in vertical axial section, of a central feed conduit air separator provided with the preferred form and combination of my present improvements, cut on the lines 1—1 in Fig. 2;

Fig. 2 is a fragmentary cross section thereof, the left hand side of the view being cut on the plane of the fulcrum of the counterbalanced lever, and the other parts of the view being stepped down and cut on planes, the one extended above the fan blades, the next extended immediately below them, the next extended immediately above the annular baffle, the next extended immediately above the lower baffle, the next extended immediately below the latter, the next extended immediately below the distributor, and the next through the filter vanes, these planes being approximately indicated by the dotted lines 2 in Fig. 1, and

Fig. 3 is a fragmentary horizontal section of 35 the drive shaft, the view being cut approximately on the plane of the line 3 in Fig. 1, and similarly stepped down for showing the segments of the lower baffle and distributor in plan.

Referring to the drawings, in which the same numbers indicate similar parts of an air separator, 11 is the outer casing enclosing a settling chamber 13, 15 is an inner casing enclosing a separating chamber 17, 19 is a coarse material receiver, 21 is a supply conduit, 23 is a rotary distributor, 25 is a distribution chamber, 27 is the distributor drive shaft, 29 are its drive gears, 31 is a lower current inlet to the separating chamber, 63 is an upward current passage therein, 33 is an upper current outlet therefrom, 35 are the blower fan blades for circulating a separating current up through the separating chamber and down through the settling chamber, 125 are the fan spokes, 37 is the return current passage, 39 is a filter consisting of one or more rings of circumferentially spaced vertical vanes across the return current passage, for intercepting and dropping through their open lower ends fine material in the current returning from the settling chamber, 41 is the fan drive shaft, 43 are the fan gears, 45 is a variable speed motor or other primary driver, 47 is an outlet for fine material, 49 is an outlet for coarse material, 61 is a rotary upper valve, opposite and extended outwardly across and above the upper outlet 33, for defining the space between the upper valve and the upper outlet through which said current may flow from the upper outlet, 67 is an annular baffle within the separating chamber and between the distributor 23 and the outlet 33 for defining the path through which said current may flow therebetween, 71 are rotary up-tossers around the distributor 23, for up-tossing distributed material, 53 is a lower baffle above and adjacent the distributor, 51 and 55 are rotary rings 76

of radially slidable segments slidably mounted around the distributor and lower baffle for radially varying the size thereof and the distribution and current space therearound, 73 is a rotary retarder shelf spaced inwardly of and above the lower inlet 34, and above and around the return passage 37, for retarding and dropping unseparated material thereabove, 75 is a rotary tubular partition between the return current passage and the coarse receiver 19, 77 is a rotary shelf below the filter vanes for resisting leakage thereunder, 79 is a rotary grooved ring around the receiver 19 for resisting leakage therearound, 81 is a vapor outlet pipe within and encircled by the partition 75, 83 is a vertically adjustable current deflector above and spaced around the filter 39, 85 are jarmer hammers between the inner and outer casings, 87 is a revoluble gravity striker for operating these hammers, 89 is a vertical anvil in communication from the striker 87 to the hammers 85, for vibrating the latter, 131 are conically arranged rings for carrying the filter vanes, 133 is a suspender rod therefor and for the inner casing, 143 is an adjuster nut for vertically adjusting these, 137 are vertically slidable radial guides therefor, and 139 is an annular conical deflector valve around the outer edges of the fan blades 35, which deflector valve with the deflector ring 83 is vertically adjustably carried by a rod 141, which also carries whirl checks 135 which are disposed between the spaced reversely cone rings of the deflector 83 to check whirling of current therebetween.

These parts may be of any suitable construction for the distribution of material to be separated in the distribution chamber 25 and for causing a current to flow up through the separating chamber and upper outlet into the settling chamber, and to return through the lower inlet, for separating and floating fine material into the settling chamber, and for dropping coarse material into the receiver.

The distributor and its hub or lower baffle have been rotatable at variable speed, for varying the rate of supply and the velocity of distribution of the material to be separated, and have been vertically adjustable for vertically varying the zone of distribution, and have been radially adjustable for radially varying said zone and the width of the distribution chamber, for varying the separation, and the annular baffle has been vertically adjustable for varying the height of the selection chamber above it, for varying the separation, and the upper valve has been rotatable for discharging material from it, and has been vertically or radially adjustable for varying the space through which the current may flow from the upper outlet, for varying the velocity of the current, for varying the separation, and these parts have been revolubly suspended from an upwardly and downwardly movable bearing 91, mounted on a lever 93, counterbalanced by weights 97, carried therefrom by a screw threaded rod 99, and adjusted by a nut 95, the manipulation of which simultaneously vertically adjusted the distribution means in one direction and the valve means in the reverse direction at the same time, as claimed in my said application Serial No. 55,423 or adjusted the distribution means and relatively adjusted the upper baffle at the same time, as claimed in my said application Serial No. 1,173, for simultaneously varying the zone of distribution and the velocity of the separating current, and the fan blades have been variable or rotatable at variable

speed coincidently with variation of the speed of rotation of the distributor, for varying the velocity of circulation of the current coincidently with variation of the velocity of the distribution of said material, as shown in my said Patents Nos. 1,876,516 and 1,987,615, and coincidently with variation of the zone of distribution, or movable adjustment of the upper baffle, as claimed in my said application Serial No. 1,173, for varying said velocity of circulation coincidently with variation of the zone of distribution and of the space through which the current may flow below and to the outlet.

According to my present invention I preferably movably adjust the distributor 23 and the upper valve 61 in the same direction and to the same extent at the same time and by one manipulation, and thereby by increase the space through which the current may flow, and the velocity of the separating current simultaneously with elevation of the zone of distribution, and vice versa, and I accomplish this by making the vertically adjustable lower distribution means, and vertically adjustable upper valve, in fixed vertical relation throughout their vertical adjustments, preferably by fixedly mounting each on a vertically movable suspender 59, shown as within and vertically slidably through and revoluble relatively to the fan shaft 41, and as splined to and revoluble with and around and vertically slidably relatively to the distributor shaft 27, and as extended up through and revolvably mounted on the vertically adjustable bearing 91, adjustment of which vertically adjusts the distributor and upper valve in the same direction and to the same extent and at the same time.

According to another feature of my present invention I make the annular baffle 67 vertically movable from an active position adjacent the distributor and below the selection chamber 65, in which position it sinuously directs the path of the current into the latter, to an inactive position above the selection chamber 65, in which position it practically eliminates the selection chamber and is disposed under and adjacent the upper outlet 33, and thereby affords a more direct current passage from the distribution chamber 25 to the upper outlet 33, which is desirable for coarse separation. To accomplish this I preferably make the annular baffle 67 move in the same direction as, but to a greater extent than, the upper valve 61 moves, by multiplying its movement relatively to the latter and making both move simultaneously in the same direction but to relatively different extents, whereby the baffle 67 may be made active or inactive as the intensity of the current is decreased or increased and as the zone of distribution is lowered or raised. In its lower or active position the baffle 67 is above and adjacent the upholders 71 and intercepts and rotatably discharges upthosser particles thereabove and thereby resists their entrance into the selection chamber 65, and in its upper or inactive position it is remote from the upholders 71 and facilitates passage of such particles to the upper outlet 33.

Any suitable means may be employed for multiplying movement of the baffle 67 relatively to that of the distributor 23 or the upper valve 61, but I prefer to effect this simultaneously with their movement by means of a motion multiplication lever 69 which is fulcrumed on the hub or lower baffle 53, and the long arm of which carries the annular baffle 67, and the short arm of which extends through a slot 147 in the sus-

pender 59 and engages a hole 149 in the distributor shaft 27 so that when the suspender is raised relatively to this shaft the lever 69 will be swung and its long end will raise the baffle 67 to adjacent the outlet 33.

Another feature of my present invention provides for radially sliding one or both the rotary rings of segments 51 and 55 from above the lower baffle 53 and preferably coincidently with 10 vertical adjustment thereof, which may be accomplished in any suitable manner, but for which I preferably provide bell cranks 57, which are fulcrumed on the lower baffle 53, and have one arm connected to the segments 55 and the other 15 arm extended through one of the slots 147 in the suspender 59 and in engagement with one of the holes 149 in the distributor shaft 27 in such manner that when the suspender is raised relatively to this shaft the bell cranks will be 20 tilted to the end of radially sliding the segments outwardly for thereby varying the width of the upward passage 63 around them. The segments 55 are preferably slidably mounted on top of the lower baffle 53 and the segments 51 are preferably 25 slidably mounted against the underside of the distributor 23, and these segments are preferably connected together so that they will slide radially at the same time. They are moved outwardly for coarse separation and inwardly for 30 fine separation simultaneously with vertical movement of the distributor and the upper baffle.

In the construction shown the inner ends of the levers 69 and of the bell cranks 57 are extended through the slots 147 in the distributor 35 suspender 59 and into the holes 149 in the distributor drive shaft 27, and thus serve to spline the suspender 59 to the shaft 27 in such manner that the suspender 59 and the shaft 27 must 40 rotate together while the suspender 59 may be moved vertically relatively to the shaft 27 as the bearing 91 for the suspender is raised or lowered for movably adjusting the distributor 23 and the valve 61 and annular baffle 67 from their lower positions shown in full lines in Fig. 1 to their 45 upper positions shown in dotted lines in said figure. In this construction the shaft 27 and suspender 59 are shown as revoluble relatively to and revolvably mounted inwardly of the tubular blower shaft 41 for rotating the fan blades 50 35, an arrangement which is desirable in the type of separator in which the distributor and the fan blades are relatively rotatable.

The distributor and upper valve are preferably 55 rotatable relatively to the fan blades in the construction shown, which comprises a variable speed distributor driver 103 and a variable speed blower driver 105, the constant speed shafts 177 of both 60 preferably being the variable speed shaft of a variable speed driver 101, the constant speed shaft 121 of which is preferably rotated by the motor 45 or other primary source of power.

In the construction shown the distributor driver 103 has a variable speed shaft 111, which is belted to the distributor gear shaft 113, and the blower driver 105 has a variable speed shaft 111 which is belted to the blower gear shaft 115.

Each variable driver is shown as having shifter levers 109, those of the driver 101 being manually adjusted as by a screw 119.

According to another feature of my invention the speed of rotation of the distributor 23 and the upper valve 61 is automatically varied as these are simultaneously adjusted in the same direction and to the same extent at the same time, and preferably the speed of rotation of the

fan blades is automatically relatively varied coincidently with such adjustment.

According to other features of my invention the velocity of the circulation of the current is varied by and coincidently with variation of the means for varying the space through which the current may flow, and is preferably increased with increase in such space, and is preferably so varied coincidently with variation of the zone of distribution, and the space through which the current may flow is preferably varied coincidently with such variation of the velocity of the circulation of the current and coincidently with variation of the zone of distribution, and the physical characteristics of the separating chamber itself are preferably varied from one comprising a contracted circuitous passage between the distribution means and the upper outlet, for effecting fine separation, to one comprising an expanded direct current passage therebetween, for effecting coarse separation, and variations in the velocity of the distribution of the material to be separated, and in the velocity of the circulation of the current, and of the space through which the current may flow, are preferably effected coincidently with such variations of the physical character of the separating chamber itself, for effecting which variations coincidently my present invention preferably provides an operative connection between and in operative relation to a current space variation means, such as the rotary valve 61 for varying the space through which the current may flow, or the rotary annular baffle 67 movable from with a lower part 35 of the separating chamber and around a lower part of the upward passage to above the latter and adjacent and around the upper outlet, constructed and arranged to vary the variable driver means for increasing the speed of rotation of the current circulation means coincidently with movement of the space variation means toward an open position, or coincidently with movement of the annular baffle from within and around to above the separating chamber, or vice versa.

This may be accomplished in any suitable manner but preferably I accomplish it from the adjustment means 93 common to the distributor 23 and the valve 61, by connecting an upper arm 107 of the lever 93 with the shifter levers 109 of the distributor driver 103, and by connecting a lower arm 107 of the lever 93 with the shifters 109 of the blower driver 105 in such manner that as the distributor 23 and valve 61 are lowered their driver 103 will be varied to increase their speed of rotation, and the blower driver 105 will be varied to decrease its speed of rotation, when such relative variation is desired.

This variation of the speed of rotation of the distributor is especially desirable when the segments 51 and 55 are used and are retracted for increasing the width of the distribution chamber 25 and thereby decreasing the intensity of the separating current therein as the distributor 23 is lowered, for fine separation, as then it is desirable to increase the speed of rotation of the distributor sufficiently to enable it to centrifugally project the distributed material across the then relatively wide distribution chamber, and when the segments are used with and radially extended relatively to a distributor as it is raised to the 70 position shown in dotted lines in Fig. 1 for radially increasing its size and decreasing the radial width of the distribution chamber 25 around it, and thereby increasing the intensity of the current flowing past it, for coarse separation, it then 75

is desirable that the speed of rotation of the distributor should be diminished, in order that the velocity of its centrifugal discharge of the material across the then narrow distribution chamber shall not be so rapid as to resist separation.

This variation of the speed of rotation of the blower is especially desirable when the upper valve 61 and the lower distributor 23 are moved in the same direction and to the same extent at the same time, to the end that when the space through which the current may flow is diminished by the lowering of the valve 61 and the area of the distribution chamber 25 is increased by the retraction of the segments 51 and 55, the velocity of the circulation of the current may be simultaneously modified coincidently with the throttling of said space by lowering the valve 61 for fine separation. Increased speed of rotation of the blower is desirable coincidently with elevation of the distributor 23 and the upper valve 61, in order that simultaneously therewith the velocity of the circulation of the current may be increased coincidently with decrease in the width of the distribution chamber and increase in the space through which the current is permitted to flow from the separating chamber.

According to another feature of my present invention I conserve height in the construction of the separator by mounting the fan spokes 125 on a fan hub 145 which is extended and disposed within the hollow or recessed upper side of the upper valve 61, which latter is mounted below and extended upwardly and outwardly around this hub to adjacent the inner edges of the fan blades and has its outer edge movable from below and adjacent the spokes 125 to above and near the outlet 33, and within and above its upper side it is connected to its suspender 59, which is slideable up through the fan hub 145 for suspending the valve from within or through the latter and for adjustably moving it from thereabove. As shown the suspender 59 is around and slideable on the distributor shaft 27, and is splined thereto by the inner ends of the bell cranks 57 and the levers 69 which spline it thereto by passing through the slots 147 in the suspender 59 and entering holes 149 in the shaft 27, which is vertically stationary as the suspender 59 is vertically slid axially of it.

Another feature of my present invention suspends and rotates the annular retarder 73, the tubular partition 75, the rotary shelf 77, and the rotary ring 79 from the distributor drive shaft 27, as by circumferentially spaced hangers 151 connected to the end of this shaft above the distributor and inwardly of and encircled by its hub or lower baffle 53 and extended therefrom down through the distributor in such manner that the latter when vertically adjustable may be slid relatively to the hangers and the parts sustained thereby, for vertically stationarily positioning these a spaced distance below the adjustable distributor which rotates therewith.

Another feature of my present invention extends the rotary ring 79 from below to above the lower ends of the filter vanes 39, whereby to resist inflow of current between these ends for which purpose I preferably extend the ring 79 from above to below the upper edge of the receiver 19, with its inner annular groove portion spaced around this edge, and its lower portion below this edge connected to the rotary shelf 77 below the lower ends of the vanes 39, in conjunction with which it serves to enclose the lower ends of these vanes and to resist inflow there-

through as the shelf 77 resists upflow therebetween and as its groove portion resists leakage between it and the edge of the receiver 19.

Another feature of my present invention preferably makes the deflector 83 concentrate the separating current into a downward jet intermediate and a spaced distance from the cylindrical walls of the outer casing and the separating chamber, for which purpose I preferably form it of concentric, reversely tapered conical rings, 10 which are radially spaced from each other by circumferentially spaced whirl checks 135 therebetween, and which have lower edges radially spaced from said walls respectively, and which are thereby adapted to jet the separating current 15 downwardly a spaced distance therefrom and a substantial distance radially outwardly of and around the vanes 39. Thus downwardly jetting the dust laden current tends to impel particles floating therein past the vanes 39 and into the 20 dust chamber 13 as the current tends to change its direction toward and between the vanes 39.

Another feature of my present invention preferably provides the outer casing with vertically adjustable and reversible supports or feet 153, 25 which preferably have an L shaped portion slidably and reversely adjustably bolted to any one of a plurality of holes in vertically extended members or legs 155 provided on the outer casing 11, in such manner that the height of any foot 153 30 may be adjusted for mounting the separator on a support below it, or the feet may be inverted for suspending the separator from an upper support.

In operation with the construction shown the zone of the distribution, the velocity of the distribution, the velocity of the circulation, and the space through which the current may flow, will be coincidently varied by vertically adjusting the upper valve and the lower distributor in the same direction and to the same extent at the same time 35 by one manipulation. When the annular baffle 67 is used it will by the same manipulation be simultaneously adjusted from below to above the selection chamber. When the segments 51 and 55 are employed for radially varying the size of 40 the space therearound they will be simultaneously adjusted by the same manipulation. When the variable speed driver 103 is used for the distributor its speed of rotation will be automatically varied simultaneously with coincident adjustment of the distributor and the upper valve, and when the variable speed driver 105 is used with the fan blades 35 its speed of rotation will be automatically varied simultaneously with such coincident adjustment of the distributor 23 and 45 upper valve 61.

It will be understood that my present invention is not limited to the particular details of construction, arrangement, use or combination, of features set forth as constituting the preferred 50 form thereof, since it may be availed of in whole or in part according to such modifications of these as circumstances or the judgment of those skilled in the art, may dictate, without departing from the spirit of the invention.

What I claim is:

1. In a current separator comprising, a settling chamber, a separating chamber having a lower current inlet and an upward current passage and an upper current outlet in communication therewith, a distributor spaced below said outlet and within said passage, for the supply and distribution of material to be separated therein, and movably adjustable relatively to said outlet for varying the zone of said distribution,

for varying the separation, rotary blower means comprising spoke means having fan blades above said outlet for upflowing a separating current through said passage, for the separation of fine material therein, and a valve above and adjacent said outlet, for defining the space through which said current may flow therefrom, and movably adjustable for varying said space, for varying the velocity of said current, for varying said separation; the combination therewith of an adjuster common to and in operative relation to said distributor and said valve, for movably adjusting said distributor and said valve, connected to and movable simultaneously with and in the same direction as said distributor and said valve, and operable to simultaneously adjust said distributor and said valve in the same direction, and thereby to vary said velocity adjacent said outlet coincidently with variation of said zone below said outlet, for varying the separation.

2. In the separator specified in claim 1, said adjuster being vertically movable, and being operable to vertically movably adjust said distributor and said valve in the same direction.

25 3. In the separator specified in claim 1, said adjuster being in vertically fixed relation to said distributor and said valve, and being operable to simultaneously movably adjust said distributor and said valve in the same direction.

30 4. An air separator for grading materials comprising, in combination, an outer casing enclosing a settling chamber, an inner casing enclosing a separating chamber having a lower inlet and an upper outlet in communication with said outer chamber, blower means for causing a fluid current to flow up through said separating chamber and to return through said outer chamber, for separating and floating fine material into said outer chamber, a distributor in said separating chamber, for receiving and delivering material to be separated therein, and a tailings receiver within said outer chamber and having an open end spaced around said lower inlet, for receiving tailings dropping through said lower inlet, and for affording a return current passage from said outer chamber to said lower inlet; the combination therewith of a rotary, open-topped, tubular partition wall, within and in communication between said separating chamber and said receiver, and within and spaced inwardly of said lower inlet, between said distributor and said receiver, and inwardly of and encircled by said return current passage, and adapted to rotatably partition the latter from the space below said distributor and above said receiver, and to afford current communication within said wall, through said space, for rotatably defining the path of said returning current, and for returning current within said tubular wall from the space within said receiver to said separating chamber.

45 5. In the separator specified in claim 1, said distributor comprising a rotary ring of radially slidably adjustable segments outwardly slidable coincidently with similar upward movement of said distributor and said valve, to decrease the radial width of said zone simultaneously with said upward movement of said distributor and said valve, and thereby to increase the intensity of said current around said distributor coincidently with said increase of said intensity above said outlet.

60 6. In the separator specified in claim 1, said distributor comprising a lower baffle spaced above

and adjacent and vertically movable with it which comprises a rotary ring of radially slidably adjustable segments which are outwardly slidable coincidently with collective upward movement of said distributor and said valve, and are thereby operable to decrease the radial width of the current passage above and adjacent said zone, whereby to increase the intensity of said current around said baffles, coincidently with collective upward movement of said distributor and said valve, for increasing said intensity adjacent said zone coincidently with increase of said intensity above said outlet.

7. A current separator comprising, a settling chamber, a separating chamber having a lower current inlet and an upward current passage and an upper current outlet in communication therewith, distribution means spaced below said outlet and within said passage, for the supply and distribution of material to be separated therein, and blower means in communication with said outlet, for upflowing a separating current through said passage for the separation of fine material therein; the combination therewith of an annular baffle within said separating chamber, between said distribution means and said outlet and around said upward passage, for defining the path through which said current may flow from above said distribution means to said upper outlet, and vertically adjustable for varying said path, for varying the separation, said annular baffle being vertically adjustable from above and adjacent said distribution means, for defining a circuitous path thereabove, to below and adjacent said outlet, for defining a less circuitous and more direct path for said current between said distribution means and said outlet.

20 8. In the separator specified in claim 7, said distribution means being vertically adjustable for vertically varying the zone of distribution, and said annular baffle being vertically adjustable in the same direction as and to a greater extent than and simultaneously with said vertical adjustment of said distribution means, and being thereby operable to define a circuitous path for said current coincidently with depression of said zone, and a more direct path for said current coincidently with elevation of said zone, for varying the separation simultaneously with vertical variation of said zone.

25 9. In the separator specified in claim 7, said distributor and said annular baffle being relatively vertically adjustable in the same direction and at the same time, for simultaneously varying said zone and said path, and being connected by a motion multiplication connection in operative relation to each and operable to move the annular baffle from, and a multiplied distance relatively to the movement of, the distributor coincidently with movement of the latter.

30 10. In the separator specified in claim 7, a valve above said outlet, for defining the space through which said current may flow therefrom, and vertically adjustable for varying said space, for regulating the intensity of said current, for varying the separation, and said annular baffle being in operative relation to said valve and being movable simultaneously with and in the same direction as and to a greater extent than the movement of said valve, and being thereby operable to define said circuitous path when said valve is moved downwardly for diminishing the intensity of said current, and to define said

direct path when said valve is moved upwardly for increasing the intensity of said current, whereby to vary said path coincidently with said regulation of said intensity.

5 11. In the separator specified in claim 7, said distribution means comprising a ring of collectively radially slideable adjustable segments inwardly of and adjacent and concentric of the zone of said distribution, and radially inwardly and outwardly slideable relatively thereto for radially varying the width of said passage adjacent said zone for varying the intensity of said current adjacent thereto, for varying the separation, and said annular baffle being vertically movable simultaneously with said radial movement of said segments, from a lower position above and adjacent thereto when said segments are moved radially inwardly, and then operable to define a circuitous path for said current thereabove, to an upper position below and adjacent said outlet when said segments are moved radially outwardly and then operable to define a more direct path for said current between said segments and said outlet, for varying said path coincidently with radial variation of said passage around said segments.

12. A current separator comprising, a settling chamber, a separating chamber having a lower current inlet and an upward current passage and an upper current outlet in communication therewith, a rotary distribution means spaced below said outlet and within said passage, for the supply and distribution therein of material to be separated therein, and movably adjustable relatively to said outlet, for varying the zone of said distribution, for varying the separation, rotary blower means in communication with said passage, for the upflow of a separating current therethrough, for the separation of material therein, and a rotary valve above said outlet and in the path of said current, for defining the space through which said current may flow, and movably adjustable for varying said space, for varying the velocity of said current, for varying said separation; the combination therewith of adjustment means common to and in operative relation to said distribution means and said rotary valve, for movably adjusting each thereof, connected to and movable simultaneously with and in the same direction as said distribution means and said rotary valve, and being operable to simultaneously adjustably move said distribution means and said rotary valve in the same direction, and being thereby operable to vary said velocity coincidently with said variation of said zone of distribution.

13. In the separator specified in claim 12, said adjustment means being rotatable with said rotary distribution means and with said rotary valve, and being operable during said rotation to adjustably move said distribution means and said rotary valve in the same direction.

14. In the separator specified in claim 12, said adjustment means being vertically movable and being in vertically fixed spaced relation to said distribution means and to said rotary valve, and being operable to vertically adjust said distribution means and said rotary valve in the same direction and to the same extent at the same time.

15. An air separator for grading materials comprising, an outer casing enclosing a settling chamber, an inner casing enclosing a separating chamber having a lower inlet and an upper outlet in communication with said outer chamber,

blower means for causing a fluid current to flow up through said separating chamber and to return through said outer chamber, for separating and floating fine material into said outer chamber, a distributor in said separating chamber, for receiving and delivering material to be separated therein, and a tailings receiver within said outer chamber and having an open end spaced around said lower inlet, for receiving tailings dropping through said lower inlet, and for affording a return current passage from said outer chamber to said lower inlet; the combination therewith of a rotary annular tailings retarder around and above said return current passage and within and above and spaced inwardly of said lower inlet.

16. A current separator comprising, a settling chamber, a separating chamber having a lower current inlet and an upward current passage and an upper current outlet in communication therewith, supply means spaced below said outlet and within a lower portion of said passage, for the supply therein of material to be separated therein, and current circulation means in communication with said outlet, for upflowing a separating current through said passage, for the separation therein of said material; the combination therewith of a movable annular wall within said separating chamber and above said supply means and below said upper outlet, for defining the volumetric area of said upward passage below said wall and above said supply means, and movable within said separating chamber from above and adjacent said supply means, for contracting the volumetric area of said upward passage below said wall and above and adjacent said supply means, to above said separating chamber and remote from said supply means and adjacent said upper outlet, for expanding said area, for varying the velocity of said current upflowing within said separating chamber below said wall and above said supply means coincidently with said variation of said volumetric area of said upward passage below said wall and above said supply means, for varying said separation.

17. A current separator comprising, a settling chamber, a separating chamber having a lower current inlet and an upward current passage and an upper current outlet in communication therewith, supply means spaced below said outlet and within a lower portion of said passage, for the supply therein of material to be separated therein, and current circulation means in communication with said outlet, for upflowing a separating current through said passage, for the separation therein of said material; the combination therewith of a rotary movable annular wall within said separating chamber above said supply means and below said upper outlet, for rotatably defining the volumetric area of said upward passage below said wall and above said supply means, and movable within said separating chamber from above and adjacent said supply means, for contracting the volumetric area of said upward passage below said wall and above and adjacent said supply means, to above said separating chamber and adjacent said upper outlet, for expanding said area, for varying the velocity of said current upflowing through said upward passage, for varying said separation.

18. In a current separator comprising, a settling chamber, a separating chamber having a lower current inlet and an upward current passage and an upper current outlet in communication therewith, supply means below said outlet and within a lower portion of said passage, for

the supply therein of material to be separated therein, rotary blower means in communication with said passage, for the upward circulation of a current therethrough, for the separation of said material therein, variable speed rotation means in operative relation to and for rotating said blower means, and variable for rotating the latter at variable speed, for varying the velocity of said current, for varying said separation, and a movably adjustable annular wall within said separating chamber above said supply means and below said upper outlet, for defining the volumetric area of said upward passage below said wall and above said supply means, and movable from above and adjacent said supply means, for contracting said area, to adjacent said upper outlet, for expanding said area, for varying the velocity of said current flowing through said upward passage, for varying said separation; the combination therewith of an operative connection in operative relation to said movable wall and to said variable speed rotation means, for varying the latter coincidently with said movement of the former, operated with said movement of said movable wall, constructed and arranged to vary the speed of said variable speed rotation means coincidently with said movement of said annular wall, and being operable to vary the velocity of the circulation of said current coincidently with variation of the volumetric area of said upward passage.

19. In a current separator comprising, a settling chamber, a separating chamber having a lower current inlet and an upward current passage and an upper current outlet in communication therewith, supply means below said outlet and within said passage, for the supply therein of material to be separated therein, rotary current circulation means in communication with said passage for the upward circulation of a current therethrough, for the separation of said material therein, variable speed rotation means in operative relation to and for rotating said circulation means, and variable for rotating the latter at variable speed, for varying the velocity of said circulation, for varying said separation, and current space variation means in the path of said current, for defining the space through which

said current may flow, and variable for varying said space, for varying the velocity of said current, for varying said separation; the combination therewith of an operative connection in operative relation to said current space variation means and said variable speed rotation means, for coincidently varying each thereof, operated with variation of said current space variation means, and being operable to vary said variable speed rotation means coincidently with variation of said space variation means, and being thereby operable to vary the velocity of the circulation of said current coincidently with variation of the space through which said current may flow.

20. In a current separator comprising, a settling chamber, a separating chamber having a lower current inlet and an upward current passage and an upper current outlet in communication therewith, rotary distribution means below said outlet and within said passage, for the supply and distribution therein of material to be separated therein, and rotatable at variable speed, for varying the velocity of said distribution, variable speed rotation means, for rotating said distribution means, and variable for varying the speed of rotation of the latter, current circulation means in communication with said passage, for the upward circulation of a current therethrough, for the separation of material therein, and a current space variation valve in the path of said current for defining the space through which said current may flow, and variable for varying said space, for varying the velocity of said current, for varying said separation; the combination therewith of an operative connection in operative relation to said current space variation valve and said variable speed rotation means, for varying the latter coincidently with variation of the former, operated with variation of said current space variation valve, constructed and arranged to vary the speed of said variable speed rotation means coincidently with variation of said current space variation valve, and being operable to vary the velocity of said distribution coincidently with variation of the space through which said current may flow.

GEORGE HOLT FRASER.
